MULTIPLE CYLINDER ENGINE OF THE
MULTIPLE PISTON TYPE

David Adams, Detroit, Mich.

Application January 16, 1948, Serial No. 2,687

8 Claims. (Cl. 123—51)

1

This invention relates to a multiple cylinder engine of the multiple piston type and has for its primary object to simplify the construction and operation of engines of this character.

Another object is to improve the efficiency of this type of engine and to reduce the number of working parts to a minimum.

A further object is to separate the lubricant employed in the crank case from the lubricant employed for lubricating the valve actuating mechanism and to simplify the construction of the valve actuating mechanism through the elimination of push rods, rock arms and the like.

A still further object is to effectively separate the engine cooling fluid from the lubricants employed for lubricating the working parts of the engine and at the same time to provide adequate cooling, and adequate lubrication for the engine.

The above and other objects may be attained by employing this invention which embodies among its features spaced parallel cylinders, aligned valves opening into adjacent cylinders, and a cam operating between each pair of cylinders, for opening said valves.

Other features include a trough extending longitudinally along the underside of the engine for containing a pool of lubricant in which the lowermost portions of the valve actuating cam disks are immersed, and arcuate hoods between the cylinders for enclosing the upper portions of the cam disks and separating the cooling fluid from the lubricant contained in the trough.

Still other features include pistons having diametrically opposed semi-conical recesses adjacent their heads, and conical headed valves operating in diametrically opposed relation in the cylinders.

In the drawings:

Figure 1 is a top plan view of an engine embodying the features of this invention.

Figure 2 is a front end view in elevation of the engine illustrated in Figure 1.

Figure 3 is a side view of the engine illustrated in Figure 1.

Figure 4 is a rear end view of the engine illustrated in Figure 1 showing portions of the gear case broken away, more clearly to illustrate certain details of the invention.

Figure 5 is a horizontal sectional view taken substantially along the line 5—5 of Figure 2.

Figure 6 is a top plan view of the engine showing the top cover plate removed.

Figure 7 is a longitudinal sectional view taken substantially along the line 7—7 of Figure 1.

Figure 8 is a fragmentary enlarged sectional view similar to Figure 7.

2

Figure 9 is a transverse sectional view taken substantially along the line 9—9 of Figure 5,

Figure 10 is a transverse sectional view taken substantially along the line 10—10 of Figure 5,

Figure 11 is a perspective view of the intermediate partition which separates the cooling fluid chamber from the lubricant-containing trough,

Figure 12 is a fragmentary enlarged sectional view showing a portion of an engine cylinder with a valve open,

Figure 13 is a fragmentary sectional view taken substantially along the line 13—13 of Figure 12,

Figure 14 is a perspective view of the bottom pan of the engine showing the lubricant retaining trough assembled with relation to the bottom crank cases,

Figure 15 is a perspective view of one of the end plates of the crank case,

Figure 16 is a perspective view of a shield such as is employed on the exhaust valves of the engine,

Figure 17 is a perspective view of one of the valves showing adjacent thereto a typical adjusting collar,

Figure 18 is a perspective view of one of the pistons and its associated connecting rod, and

Figure 19 is a perspective view of one of the valve actuating cam disks.

Referring to the drawings in detail, the main portion of the engine comprises a pair of spaced parallel side plates 20. These plates are provided with longitudinally spaced aligning openings 22 for the reception of the reduced ends 24 of longitudinally spaced cylinders 26. Formed in the side plates 20 adjacent the cylinders 26 are aligning openings 28 for the reception of through bolts 30 which extend transversely across the engine and bind the side plates 20 against the shoulders formed at the ends of the cylinders 26 by the reduced portions 24. Crank bearings 32 are clamped against the outer sides of the plates 20 to form supports for longitudinally extending crank shafts 34, which operate about spaced parallel axes adjacent the ends of the cylinders 26. The crank shafts 34 are provided at longitudinally spaced intervals with crank arms 36, and coupled to the crank arms 36 in a conventional manner are connecting rods 38 which extend into opposite ends of the cylinders and are coupled at their ends remote from the crank arms 36 by means of conventional wrist pins 40 to pistons designated generally 42.

Each piston 42 comprises a hollow circular cylindrical body 44 provided with conventional grooves 46 for the reception of conventional pis-

ton rings which serve to engage the walls of the cylinders 26 to prevent the escape of gasses around the pistons. Each piston 42 is provided with a head 46, and formed at diametrically opposite points in the outer side of each piston at the junction of the cylindrical body 44 with the head 46 are semi-conical recesses 50 for a purpose to be more fully hereinafter described.

Entering each cylinder midway between opposite ends and lying along an axis which lies in a plane with the longitudinal axis of the engine is an intake port 52, and entering each cylinder in diametrically opposed relation to the intake port 52 is an exhaust port 54. Also entering each cylinder along an axis which lies perpendicular to and intersects the axis of the intake and exhaust ports 52 and 54 is an internally screw-threaded opening 56 for the reception of the threaded end 58 of a conventional sparkplug 60. Surrounding each opening 56 in each cylinder 26 is a radially extending boss 62 to which a nipple 64 is welded. Each nipple is provided adjacent its end remote from the boss 62 with a shoulder 66 for a purpose to be more fully hereinafter explained.

Welded or otherwise attached to each cylinder 26 and enclosing the intake port 52 therein is a duct 68 which extends upwardly and is provided adjacent its upper end with an attaching flange 70, the upper face of which lies in a plane with the shoulders 66 of the nipples 64. A similar duct 72 is welded to the opposite side of each cylinder and encloses the exhaust port 54, and like the duct 68 terminates at its upper end in an attaching flange 74, the upper surface of which lies in a plane common to the upper surfaces of the attaching flanges 70 of the intake ducts 68. The ducts 68 and 72 are provided with aligning openings 76 for the reception of valve guides 78 through which slide the valve stems of the valves to be more fully hereinafter described.

Mounted for longitudinal sliding movement in each valve guide 78 is the stem 80 (Fig. 17) of a valve designated generally 82. Each valve stem 80 is provided at one end with a valve head 84, and the opposite end of the stem is threaded as at 86 which is adapted to be threadedly received in an adjusting sleeve 88. The valve stem 80 is formed intermediate the ends of the threaded portion 86 with an annular row of transversely extending openings 90 which are adapted to cooperate with an annular row of diametrically opposed openings 92 formed in the adjusting sleeves 88 for receiving a cotter pin by which the adjustment of the sleeves 88 on the valve stems is retained. The head 84 of the valve 82 is provided on the side remote from the valve stem 80 with a conical extension 94 which when the pistons in a cylinder 26 are in their innermost position, project into the spaces formed by the recesses 50 in the pistons 42 to reduce as far as practicable the space occupied by the compressed gasses. In order to protect the valve guides 78 of the exhaust valves I equip the stem 80 of each exhaust valve with a shield 96, which is slipped over the threaded end 86 of the valve stem 80 before the application of the adjusting sleeve 88 and is held in place by friction.

Secured to the bottom edge of each side plate 20 and extending between the side plates below the lower sides of the cylinder 26 is a bottom plate 98 which is provided with longitudinally spaced openings 100 in which arch-shaped hoods 102 are fitted. These arch-shaped hoods are secured in place by screws 104 which extend through at-

taching flanges 106 which are secured as shown to the underside of the plate 98 and are preferably gasketed to form liquid-tight junctions with the plate 98. Opposite ends of the arch-shaped hoods 102 are closed by end walls 108 and the end walls 108 of the hoods 102 which face the cylinders 26 are provided with openings 110 which align with the openings 76 in the ducts 68 and 72 through which the valve guides 78 extend. As illustrated in Figure 12, each valve guide 78 is provided at one end with an outwardly extending flange 112 which engages an adjacent end wall 108 and serves as an abutment for one end of a compression coil spring 114 which surrounds the valve stem 80 of a valve 82 carried by the guide 78. The opposite end of the spring 114 bears against a washer 116 which surrounds the valve stem and abuts the inner end of the adjusting sleeve 88 thereon. It will thus be seen that the valves 82 are yieldingly urged into port closing position.

Supported on the underside of the bottom plate 98 beneath each cylinder 26 is a bearing 118 in which a cam shaft 120 is mounted to rotate. This cam shaft 120 lies along an axis below the plate 98 and in a vertical plane with the longitudinal axis of the engine. An end plate 122 is fixed to each end of each side plate 20, and to the bottom plate 98, and each end plate is formed with an opening 124 in which a cam shaft bearing 126 is fitted. The cam shaft 120 is mounted in the bearings 118 and extends through the end plates 122, and keyed or otherwise fixed to one end of the cam shaft is a drive gear 128 which has meshing engagement with drive gears 130 mounted on the adjacent ends of the crank shafts 34 previously described. A gear case 132 encloses the gears 128 and 130 and the cam shaft 120 is extended through this gear case and equipped with a suitable coupling 134 to which a driven shaft 136 is connected. Keyed or otherwise secured to the cam shaft 120 are spaced cam disks designated generally 138. Each cam disk comprises a hub portion 140 which is provided with an outwardly extending annular flange 142 which enters an arcuate hood 102 and engages the sleeves 88 on the adjacent ends of the valves 82. The flange 142 of each cam disk 138 is provided on one side with a cam face 144, and on its opposite side with a cam face 146. These cam faces 144 and 146 are arranged in diametrically opposite relation on the cam disk 138 so that as the disk is rotated, the valves 82 on opposite sides of each cam disk 138 will be alternately opened against the efforts of their respective springs 114. It will be understood of course that the cam faces 144 and 146 will be arranged in order to open the valves 82 in proper timed relation with the operation of the engine.

A cover plate 148 is secured as by screws 150 to the upper edges of the side plates 20 and the end plates 122 completely to enclose the cylinders 26 and the hoods 102 to form a chamber 152 through which the engine cooling fluid is circulated in a conventional manner. This cover plate is provided at properly spaced points with openings which register with the upper open ends of the ducts 68 and 72, and coupled to the flanges 70 of the ducts 68 through certain openings in the cover plate 148 are the branch pipes 156 of an intake manifold 158. Coupled to the flanges 70 through the cover plate 148 are the branch pipes 160 of an exhaust manifold 162, and formed in the cover plate 148 in axial alignment with 75 the nipples 64 are openings 164 through which
